US0D1048080S

(12) **United States Design Patent** (10) **Patent No.:** **US D1,048,080 S**
Chen et al. (45) **Date of Patent:** **** Oct. 22, 2024**

(54) **ELECTRONIC DEVICE WITH GRAPHICAL USER INTERFACE**

(71) Applicant: **Apple Inc.**, Cupertino, CA (US)

(72) Inventors: **Kevin Will Chen**, Cupertino, CA (US); **Alan C. Dye**, San Francisco, CA (US); **Christopher I. Wilson**, San Francisco, CA (US)

(73) Assignee: **Apple Inc.**, Cupertino, CA (US)

(**) Term: **15 Years**

(21) Appl. No.: **29/777,266**

(22) Filed: **Apr. 5, 2021**

Related U.S. Application Data

(63) Continuation of application No. 29/663,058, filed on Sep. 11, 2018, now Pat. No. Des. 915,436.

(51) **LOC (14) Cl.** **14-04**

CLAIM

The ornamental design for an electronic device with graphical user interface as shown and described.

DESCRIPTION

FIG. 1 is a front view of a display screen or portion thereof with graphical user interface showing the claimed design; and,

FIG. 2 is a front view of an electronic device having a display screen with the graphical user interface of FIG. 1 applied to the display screen.

The outer broken lines in the figures show a display screen or portion thereof, or an electronic device having a display screen, and form no part of the claimed design. The other broken lines in the figures show portions of the graphical user interface that form no part of the claimed design.
